DENTAL FLOSS APPLICATOR

Albert B. Collingbourne, Elgin, Ill.

Application June 3, 1935, Serial No. 24,650

2 Claims. (Cl. 132—91)

This invention relates to applicators for use in holding dental floss and applying the floss to the teeth.

The main object of the invention is to produce an applicator which is simple in construction, efficient for holding the dental floss taut for application to the teeth of the user, and so constructed that only one of the user's hands is required for holding the applicator in use.

10 The applicator, preferably, is designed to engage the top and bottom surfaces of the dental floss container, whereby the container and applicator may be carried as a unit when the applicator is not in use.

15 In the drawing:

Fig. 1 shows a side elevation of an applicator embodying my invention, and of a dental floss container engaged by the applicator.

Fig. 2 shows a side view of the applicator 20 with dental floss arranged thereon.

Fig. 3 is a top plan view of the device as shown in Fig. 1.

Fig. 4 is an end elevation of the applicator.

In that embodiment of my invention which I 25 have chosen for illustration in the drawing, the applicator comprises arms 10, 11, preferably parallel, and an intermediate member 12 connecting the arms 10 and 11. Preferably these parts are integrally formed of metal, and constitute a wide-based U-shaped device. In the form shown the arms and intermediate member are round in cross section and the arms 10 and 11 are provided with flattened oval shaped portions indicated at 13 and 14, respectively. The flat surfaces 13 and 14 30 are each slit or notched at two places on their outer side margins, as indicated at 15, whereby are formed tongues 16 and 17, respectively, on said arms 10 and 11. The free ends of the arms 10 and 11 are recessed at 18, said recesses extending across the end surfaces of said arms, parallel 35 with the longitudinal axis of the member 12.

The dental floss 19 is arranged on the applicator by winding one end about the tongue 16 so as to be held between the walls of the slots 15, then along arm 10 to end recess 18, across to end recess 18 of arm 11 and along arm 11 to tongue 17 about which the floss is wrapped so as to be

held securely in the slots 15. By holding one of the arms 10 or 11 the user may apply the floss 19 to the teeth, moving it back and forth between the teeth and also into and out of contact with the teeth.

A container for dental floss is shown at 20. It is in the conventional form of a cylindrical bottle with screw cap. The distance between the proximate portions of the arms 10 and 11 is equal to the length of the container 20. Thus the floss holder may be carried by the applicator and the two may form a unit when the applicator is not in use. As shown in the drawing the inner margins of the flattened portions 13 and 14 of the arms engage the container 20, but the form of 15 these members may be altered without departing from my invention. The member 12 may also be flattened to provide room for a name or the like.

Changes may be made in details of construction without departing from the scope of my invention and I do not intend to be limited to the exact form shown and described, except as set forth in the appended claims.

I claim:—

1. An applicator for dental floss comprising a 25 body member and spaced apart arms extending substantially at right angles to the body member from the ends of the body, the arms being provided between their ends, on their inner sides, with curved edges adapted to engage the bottom 30 and cover of a floss-holding vial, and notched portions on the outer side of each arm, each of said arms being grooved in its free end.

2. An applicator for dental floss comprising a body member, round in cross section, and spaced 35 apart arms extending substantially at right angles to the body member from the ends of the body, the arms also being round in cross section but flattened between their ends, and provided on the inner edges of said flattened portions 40 with curved surfaces adapted to engage the bottom and cover of a floss-holding vial, and notched portions on the outer edge of said flattened portions, each of the arms being grooved in its free end.

ALBERT B. COLLINGBOURNE.
